(57) **CLAIM**

The ornamental design for a clip, as shown and described.

DESCRIPTION

FIG. 1 is a front perspective view of the clip;
FIG. 2 is a left side view of the clip of FIG. 1, the right side view is a mirror image of the left side view;
FIG. 3 is a front elevation view of the clip of FIG. 1;
FIG. 4 is rear elevation view of the clip of FIG. 1;
FIG. 5 is a top plan view of the clip of FIG. 1; and,
FIG. 6 is a bottom plan view of clip of FIG. 1.
The clip is shown broken away in the middle to indicate that it has no particular length beyond what is shown.
